No. 37,273.

Patented December 20, 1904.

UNITED STATES PATENT OFFICE.

EMANUEL B. ADLER, OF PITTSBURG, PENNSYLVANIA, ASSIGNOR TO
H. ADLER COMPANY, OF PITTSBURG, PENNSYLVANIA, A CORPO-
RATION OF PENNSYLVANIA.

DESIGN FOR A HEATING-STOVE.

SPECIFICATION forming part of Design No. 37,273, dated December 20, 1904.

Application filed July 14, 1904. Serial No. 216,589. Term of patent 7 years.

To all whom it may concern:

Be it known that I, EMANUEL B. ADLER, a resident of the city of Pittsburg, county of Allegheny, and State of Pennsylvania, have invented a new, original, and ornamental Design for Heating-Stoves.

The figure is a perspective view of the heating-stove.

What I claim is—

The ornamental design for the heating-
stove, substantially as shown.

EMANUEL B. ADLER.
